(57) **CLAIM**

The ornamental design for an injection pen casing, as shown and described.

DESCRIPTION

FIG. 1 is a perspective of an injection pen casing from a front direction, showing our new design;

FIG. 2 is a perspective from a top direction;

FIG. 3 is a perspective from a bottom direction;

FIG. 4 is a front view of FIG. 1, the rear view being symmetrical;

FIG. 5 is a left side view of FIG. 1, the right side being symmetrical;

FIG. 6 is a further perspective of FIG. 1 with additional detail; and,

FIG. 7 is a perspective of FIG. 3 with additional detail. The broken lines show portions of the design that form no part of the claimed design.
